UNITED STATES PATENT OFFICE.

JAMES B. TRACY, OF MERIDEN, CONNECTICUT.

APPARATUS FOR PRODUCING MUSIC-ROLLS.

SPECIFICATION forming part of Letters Patent No. 570,352, dated October 27, 1896.

Application filed March 28, 1895. Serial No. 543,497. (No model.)

To all whom it may concern:

Be it known that I, JAMES B. TRACY, of Meriden, in the county of New Haven and State of Connecticut, have invented a new and 5 Improved Apparatus for Producing Music-Rolls, of which the following is a full, clear, and exact description.

The invention relates to the manufacture of perforated rolls or sheets used in pneumatic musical instruments for producing the 10 desired tones either pneumatically or by the aid of cylinders, combs, star-wheels, or other mechanism.

The object of the invention is to provide a 15 new and improved method of and apparatus for producing such music rolls or sheets in a very simple and comparatively inexpensive manner, and in any desired quantity, and without the use of the large stencils now employed.

The invention consists of certain parts and details and combinations of the same, as will be fully described hereinafter, and then pointed out in the claims.

25 Reference is to be had to the accompanying drawings, forming a part of this specification, in which similar letters of reference indicate corresponding parts in all the views.

Figure 1 is a sectional side elevation of the 30 apparatus. Fig. 2 is an enlarged transverse section of the same on the line 2 2 of Fig. 1. Fig. 3 is a like view of the same on the line 3 3 of Fig. 1. Fig. 4 is a similar view of the same on the line 4 4 of Fig. 1. Fig. 5 is a 35 like view of the same on the line 5 5 of Fig. 1. Fig. 6 is an enlarged sectional plan view of part of the improvement on the line 6 6 of Fig. 1, and Fig. 7 is an enlarged perspective view of one of the primary pneumatics.

40 In the manufacture of music-sheets for use in Aeolian and other pneumatic musical instruments as now practiced the notation of the score is marked in dots and dashes on a blank sheet of thick paper, and the marks then cut 45 out by hand, so as to form a pattern or stencil, which necessarily assumes large dimensions, (as much as three hundred feet long and eighteen inches wide,) and which is then used in a perforating-machine as a pattern, 50 to reproduce paper sheets of greatly-reduced size to be suitable for use in the musical instruments. The stencils are kept in stock at

the place of manufacture and are used from time to time in the perforating-machine, to form music-sheets as called for by the trade. 55 As each piece of music is represented by such a large stencil it requires the safe storing of a large number of stencils, each different from the other, to manufacture therefrom the music-sheets, and the number of stencils greatly 60 increases, as for each new piece of music desired to be added to the repertoire a stencil must be made and stored.

To avoid the storing of the stencil and permit of destroying the same after a desired 65 number of music-sheets are produced therefrom in the perforating-machine, and to be still enabled to accurately produce any desired number of music-sheets at any time 70 in the perforating-machine and use a sheet 70 which is the product of the same or any other machine designed for a like purpose after the original stencil has been destroyed, is the principal object of the invention, presently to be described in detail.

75 The apparatus as shown in the drawings is provided with dies A, mounted in a suitable framework and arranged in such a manner as to permit of passing a sheet of paper B, to be formed into a music sheet or roll, 80 between the two dies. The dies A are provided with die-apertures A', each of which is adapted to be engaged by the upper end 85 of a punch C, so that when one of the punches is pushed upward it forms a perforation or aperture in the sheet B. The several punches C are mounted to slide vertically in suitable bearings, and each punch is provided near its lower end with shoulders C' C², of which the shoulder C' is adapted to be engaged by 90 a lug D', formed on a cross-head D, fitted to slide in suitable bearings D², secured to the framework of the machine, as plainly indicated in Fig. 2.

95 The cross-head D is pivotally connected with pitmen E, engaging the crank-arms F' of the main driving-shaft F, provided with suitable pulleys F², connected by a belt F³ with machinery for imparting a rotary motion to the said shaft F. Thus when the latter is rotated the crank-arms F' and pitmen E impart a reciprocating motion to the cross-head D, the stroke of which is such that the upper end of the lug D' does not come in con-

tact with the shoulder C^2 at the time the crank-arms F' are in their uppermost position, and consequently the respective punch C is not lifted to perforate the sheet B unless 5 the projection G' of a slide G is moved upon the shoulder C^2 , so that the upper end of the lug D' engages the said projection G' and lifts the latter, and consequently the respective punch C , to cause the upper end thereof 10 to punch the sheet B . On the downward movement of the cross-head D the lug D' engages the shoulder C' to draw the punch back to its normal position, (shown in Fig. 1,) it being understood that the normal position 15 is when the upper end of the punch is below the sheet B .

Each punch C is provided with one of the slides G , and the latter are fitted to slide horizontally in suitable bearings G^2 , arranged 20 in the framework of the machine. One arm of a bell-crank lever H , fulcrumed in the framework, engages the slide G , so that when a rocking motion is given to this bell-crank lever the corresponding slide is moved forward and backward to engage and disengage 25 the shoulder C^2 for the purpose previously mentioned.

Each bell-crank lever H is connected at its rear end by a wire H' with a spring-pressed 30 arm H^2 , connected by a link H^3 with a bellows I , of the usual construction and supported in the framework of the machine. Thus for each punch C , and there are as many as fifty-eight 35 in a large perforating-machine, I provide a principal bellows I , and each bellows I is connected by a pipe J with a compound valve J' , arranged in the exhaust-chamber K , supported in the framework and provided with a primary bellows K' , similar to the bellows I 40 and adapted to actuate the valve J' , as herein-after described. The valve J' fits loosely on pins projecting from the sides of the chamber K and is engaged by the free end of the spring J^2 to hold it normally closed. The valve J' 45 carries the button-valve J^3 , which is on the outside of the chamber K and is connected to the valve J' by the stem j , as clearly shown in Fig. 1.

Each primary bellows K' is connected by a 50 pipe L with a duct N , leading to a corresponding aperture in the tracker-board O , held on the upper end of the ducts N , as illustrated in Figs. 1 and 3. In order to get more stock around each die-aperture, so as to render the 55 die more durable, the die-apertures can be alternately arranged, that is to say, the apertures can be arranged in rows, the apertures of one row being opposite the spaces between two apertures of the other row. In 60 this event the upper ends of the punches will be so shaped as to readily enter the apertures of the die, and the apertures of the tracker-board will be arranged similarly to those of the die. Over this tracker-board O passes a 65 music sheet or roll P , having the usual perforations and being one of the sheets ordina-

rily used in the Aeolian or other musical instrument. Each primary bellows is provided with a pin-aperture somewhat less than the aperture in the tracker-board, to insure a 70 rapid closing of the primary bellows after it has been actuated by inflation as the air passes through the uncovered tracker-board opening, duct N , and pipe L to the said primary bellows. Now on closing the inflated 75 bellows the air can pass through the pinhole into the exhaust-chamber to prevent the bellows from becoming wind-cramped and to insure a rapid closing. The music-sheet P is first wound on a roll Q , journaled in a bracket 80 attached to the tracker-board, and then unwinds from this roll to pass over the tracker-board O , to then pass under a guide-roll Q' , to be then connected with the holder or clamp S , secured to an endless belt or chain R , as 85 plainly indicated in Fig. 1.

The holder or clamp S is secured to the upper run of the endless belt or chain R and is adapted to clamp the front end of the sheet B , so that the latter is drawn through the dies A 90 at the same rate of speed that the sheet P is pulled over the tracker-board O , as both sheets B and P are attached to the same traveling belt or chain R by the same clamp. The belt or chain R runs over sprocket-wheels R' and 95 R^2 , journaled in the frame of the machine.

The rear sprocket-wheels R^2 are secured on a transversely-extending shaft R^3 , carrying at one outer end a ratchet-wheel R^4 , engaged by a pawl R^5 , fulcrumed on an arm R^6 , loosely 100 fulcrumed on the said shaft R^3 , and the arm is connected at its free end by a link R^7 with a crank-disk R^8 , secured on the main driving-shaft F , as is plainly illustrated in Fig. 2. Thus by the rotation of the main driving-shaft F an intermittent rotary motion is imparted to the shaft R^3 by the mechanism just 105 described, so that an intermittent traveling motion is given to the endless belt or chain R . The arrangement of the crank-arms F' and the crank-disk R^8 is such that the punches C are at a standstill during the time motion is given to the chain or belt R , and the latter is 110 at a standstill while the punches perforate the paper in the dies A , as previously explained. 115

The chambers K , containing primary bellows K' and compound valve J' , are connected by a channel K^2 with chamber T , connected with bellows U of the usual construction and provided with two exhausters V , each of 120 which is connected by a pitman V' with a crank-arm V^2 , formed on a crank-shaft V^3 , journaled in suitable bearings in the main frame. A pulley V^4 , secured on the said crank-shaft V^3 , is connected by a belt V^5 with 125 the pulley F^2 on the main driving-shaft F , so that the rotary motion of the latter is transmitted to the crank-shaft V^3 to cause the crank-arms V^2 and pitmen V' to actuate the exhausters to exhaust the air from the bellows U . Two exhausters are preferably employed, with the crank-arms V^2 set diametric- 130

ally opposite each other, as indicated in Fig. 3, so that a continuous exhausting of air from the bellows takes place.

Now it will be seen that when the several parts are in the position illustrated in Fig. 1 and motion is given to the main driving-shaft F, then the sheet B is pulled through the dies A at the same time the sheet P is drawn over the tracker-board O, and the punches C are actuated to punch the sheet B when the latter is at rest, and according to the aperture in the sheet P, that is, when an aperture in the sheet P passes over a corresponding aperture in the tracker-board O, then air can pass from the outside into the corresponding duct N and through the pipe L, connected with this duct, into the corresponding primary bellows K', expanding the same and thereby opening or lifting the valve J' and at the same time closing the button-valve J³, thus allowing a free passage of air to be drawn through the corresponding pipe J from the principal bellows I, connected with the said pipe J. This principal bellows I is thus collapsed and pulls by its link H² on its spring-pressed arm H², whereby the link H', connected with the arm H², imparts a swinging motion to the bell-crank lever H, so that the latter pushes the corresponding slide G outward to move the projection G' in engagement with the shoulder C² of the punch C, corresponding with that aperture in the sheet P in register with the apertures in the tracker-board O and the duct N. Now when the cross-head D moves upward its lug D' moves in engagement with the projection G', and consequently the punch C is raised and an aperture is punched in the sheet B, corresponding to the aperture in the sheet P in register with the duct in the tracker-board O.

When the aperture in the tracker-board O is closed by the movement of the sheet P, the expanding power of the bellows K' is lost, and valve J', button-valve J³, and primary bellows K' are instantly returned to their normal positions by the pressure of the spring J², opening the button-valve J³ to the outside, and thereby insuring a rapid return of the principal bellows I.

It is understood that one, two, or more apertures in the sheet P may pass simultaneously over the corresponding apertures in the tracker-board O, so that one, two, or more corresponding punches C are lifted simultaneously by the cross-head D to punch corresponding apertures in the sheet B. As the two sheets B and P move simultaneously the same distance, the apertures punched in the sheet B correspond exactly to those contained in the sheet P. In practice, a large number of sheets B, placed one upon the other, are pulled simultaneously through the dies A, so that a number of music-sheets are produced at the same time.

It will be seen that by the arrangement described a large and cumbersome stencil for mechanically actuating the punches C is not required. Only one of the ordinary music-sheets once produced is employed and passed over the tracker-board O, to pneumatically control the punches C to form new sheets or rolls which are an exact reproduction of the sheet P employed at the time.

Having thus fully described my invention, I claim as new and desire to secure by Letters Patent—

1. In an apparatus for producing music-rolls, the combination with a perforated tracker-board over which passes a perforated pattern-sheet, which moves in unison with the sheet to be perforated, and reciprocating punches by which the sheet is perforated, of slides controlling the movement of the punches, a bellows for each punch, bell-crank levers each having one end engaging a slide, and a pivoted and spring-pressed lever connected with the other end of the bell-crank lever and with the bellows, substantially as described.

2. An apparatus for producing music-rolls, comprising dies between which passes the sheet to be perforated, reciprocating punches in conjunction with the said dies, to perforate the sheets, each punch being provided with two shoulders, a cross-head having a reciprocating motion, and adapted to engage one of the said shoulders, a slide adapted to move in engagement with the other shoulder to be engaged by the said cross-head, and a bellows connected with the said slide to move the latter in and out of engagement with the said shoulder, substantially as shown and described.

3. An apparatus for producing music-rolls, comprising dies between which pass the sheet to be perforated, reciprocating punches in conjunction with the said dies, to perforate the said sheets, each punch being provided with two shoulders, a cross-head having a reciprocating motion, and adapted to engage one of the said shoulders, a slide adapted to move in engagement with the other shoulder to be engaged by the said cross-head, a bellows connected with the said slide to move the latter in and out of engagement with the said shoulder, a valved bellows connected with the first-named bellows, an exhauster connected with the valved bellows, and a tracker-board over which passes the perforated pattern-sheet, the said tracker-board being connected with the said valved bellows, to control the action of the valve therein, substantially as shown and described.

JAMES B. TRACY.
